(57) **CLAIM**

We claim the ornamental design for a computing device, as shown and described.

DESCRIPTION

FIG. 1 is a top, front, and right side perspective view of a computing device;

FIG. 2 is a bottom, rear, and left side perspective view thereof;

FIG. 3 is a front view thereof;

FIG. 4 is a left side view thereof;

FIG. 5 is a rear view thereof;

FIG. 6 is a second embodiment thereof showing an alternate rear view;

FIG. 7 is a right side view of the first embodiment thereof;

FIG. 8 is a top view thereof; and,

FIG. 9 is a bottom view thereof.

Broken lines shown in the drawings illustrate portions of the computing device, and form no part of the claimed design.
